(57) **CLAIM**

The ornamental design for a cable connector, as shown and described.

DESCRIPTION

FIG. 1 is a top, left perspective view of a cable connector showing my new design;

FIG. 2 is bottom, right side perspective view thereof;

FIG. 3 is a front elevation view thereof, the back elevation view being a mirror image of the front;

FIG. 4 is a top plan view thereof;

FIG. 5 is a bottom plan view thereof;

FIG. 6 is a left side elevation view thereof; and,

FIG. 7 is a right side elevation view thereof.

The broken lines in the drawing views are included for the purposes of illustrating environment and form no part of the claimed design.
